(57) **CLAIM**

The ornamental design for a shower component as shown and described.

DESCRIPTION

FIG. 1 is a perspective of the claimed design;

FIG. 2 is a top view of the claimed design shown in FIG. 1;

FIG. 3 is a bottom view of the claimed design shown in FIG. 1;

FIG. 4 is a side view of the claimed design shown in FIG. 1;

FIG. 5 is another side view of the claimed design shown in FIG. 1;

FIG. 6 is a front view of the claimed design shown in FIG. 1; and,

FIG. 7 is a rear view of the claimed design shown in FIG. 1.

The ornamental design that is claimed is shown in the drawings as solid lines and surfaces having surface shading. The evenly spaced broken lines shown in FIGS. 1-7 depict portions of the Shower Component that form no part of the claimed design.

1 Claim, 5 Drawing Sheets
